UNITED STATES PATENT OFFICE.

EDWARD JACKSON SAUL, OF DENNISTOUN, GLASGOW, SCOTLAND.

GAME APPARATUS.

Application filed March 17, 1927, Serial No. 176,238, and in Great Britain June 18, 1926.

My invention relates to improvements in 5 toys or appliances for playing games, and has for its object to provide one of a very interesting and amusing nature, and which I propose to be known as "Atsandeds".

In carrying out my invention, I provide two spindles of any convenient length and on each of which there is suitably mounted a series of sprocket wheels or such like at 10 suitable distances apart on which there are carried an endless platform made up of suitable links suitably connected together. These spindles are supported on suitable standards of different heights and rest in 15 ball bearings so that the platforms will lie at an angle or slope in the direction of their travel.

Suitably attached to each moving platform and in staggered fashion there are the 20 representations of large grotesque figures. Different designs and colours of hats are also provided and so loaded as to properly balance, stationary large grotesque figures being also placed in front of the appliance.

The apparatus can be operated by hand, 25 electric or other power provided for the purpose.

In order that my invention may be properly understood and readily carried into 30 effect, I have hereunto appended one sheet of drawings, of which

Figure 1 is a front elevation illustrating 35 my invention, with a few only of the grotesque figures shown.

Figure 2 is a side elevation.

Figure 3 is a plan of Figure 1.

Figure 4 is a view of two different forms of hats.

Referring to the drawings, A and B are 40 the spindles and C the sprocket wheels

mounted on the spindles A and B. D are the endless platforms and E and F are the standards on which ball bearings L and M carry the spindles A and B. G are the large grotesque figures suitably connected to 45 the moving platform D. H are pillars in front of the moving platform D to which large grotesque figures I are also attached. N is the pulley suitably attached to the spindle B in order to drive the appliance. J and 50 K are two forms of hats loaded at the base with rubber tubing over which the material is stitched and forms a rim for the hat.

The players are provided with many hats and, while the platform is in motion or 55 while it may be temporarily stopped, the player attempts to throw a hat on the head of one of the figures.

I claim:

1. Toys or appliances for playing games, 60 characterized in the provision of two spindles, sprocket wheels or such like mounted thereon at suitable distances apart, travelling endless platforms carried on the sprocket wheels, suitable standards of different 65 heights on which ball-bearings carry or support said spindles, large grotesque figures suitably attached to the travelling platforms and preferably in staggered fashion, combined with a hat loaded at the base with 70 rubber tubing over which the material is stitched forming a rim for the hat.

2. Toys or appliances for playing games 75 as in claim 1, characterized by the provision of pillars or such like in front of the device to which there are suitably attached fixed grotesque figures.

In witness whereof I affix my signature.

EDWARD JACKSON SAUL.
